(Cl. D58—12.6)

To all whom it may concern:

Be it known that we, William Selikoff and William B. McBride, both citizens of the United States of America and residing at Buffalo, in the county of Erie and State of New York, have invented a new, original, and ornamental Design for a Combined Case and Wrench Set Unit, of which the following is a specification, reference being had to the accompanying drawing, forming part thereof.

Fig. 1 is a top plan view of a combined case and wrench set unit embodying our new design.

Fig. 2 is a right end elevational view thereof.

Fig. 3 is a left end elevational view thereof.

Fig. 4 is a front side elevational view thereof.

Fig. 5 is a rear side elevational view thereof.

Fig. 6 is an elevational view of the bottom thereof.

Fig. 7 is a perspective view thereof showing the case opened and the wrench set exposed.

We claim:

The ornamental design for a combined case and wrench set unit, substantially as shown.

WILLIAM SELIKOFF.

WILLIAM B. McBRIDE.
